UNITED STATES PATENT OFFICE.

ARMENAG TATIOSSIAN, OF PEABODY, MASSACHUSETTS.

AUTOMATIC ELECTROMAGNETIC RAILROAD GATE.

Application filed April 30, 1928. Serial No. 273,895.

This invention relates generally to railway equipment, and has more particular reference to a novel railway safety gate.

The invention has for an object the provision of a device of the class described which is of simple durable construction, desirable and efficient in action and which can be manufactured and sold at a reasonable cost.

The device proposes the use of a railway gate tower provided with a central vertical post in which a plurality of electro-magnets are disposed in vertical rows. A support body is slidably mounted on the said vertical post and is provided with iron rollers for attraction of the electro-magnets. Counterweights are connected with the support body for normally urging same into uppermost position. Each of the electromagnets is connected with track portions so that as a train approaches the gate first the top magnets are energized to slightly draw the support body downwards, then the magnets adjacent the top magnets are energized for further drawing the support body downwards and so on until the support body reaches its lowest position. Base electromagnets are arranged for holding the support body in this position until the train passes the gate, then the counterweights raise the same. Gate elements are attached to and project from the support body operating therewith.

Obviously if the gate elements descend regularly and slowly it will not be very noticeable. A means is therefore provided for shaking and vibrating the gate elements during ascending and descending for attracting attention.

For further comprehension of the invention, and of the objects and advantages thereof, reference will be had to the following description and accompanying drawings, and to the appended claims in which the various novel feature of the invention are more particularly set forth.

In the accompanying drawing, forming a material part of this disclosure:

Fig. 1 is a plan view of a portion of railway tracks and the gate applied to a crossing thereof.

Fig. 2 is an end view of the tower of the device, a portion thereof being broken away for disclosing the counterweights.

Fig. 3 is an end view of the other side of the tower.

Fig. 4 is a front view of the tower, certain portions thereof being shown broken away.

Fig. 5 is a complete front view of the tower which is shown resting upon a pedestal.

Fig. 6 is a horizontal sectional view, taken on the line 6—6 of Fig. 2.

Fig. 7 is a similar view, taken on the line 7—7 of Fig. 2.

Fig. 8 is a schematic diagrammatical view of the wiring of the device.

The reference numeral 10 indicates generally the base of the tower, numeral 11 the roof, and numerals 12 corner angle posts connecting the base and the roof. A central vertical post 13 extends from the base to the roof and a plurality of electromagnets 14 are disposed therein in vertical rows. The post 13 consists of end plates 15 with cement 16 for holding the electromagnets, therebetween.

A support body 17 is slidably mounted on the vertical post 13, and has a plurality of rollers 18 at its top and arranged around the post 13 and bearing against the post. Iron rollers 19 are mounted on the support body and bear against the front and rear sides of the post 13. A flexible cable 20 is attached to the support body 17 at the front and rear top portions thereof and along the transverse center. It is pointed out that the support body 17 is free to tilt back and forth sideways since only two rollers 18 are arranged on the opposite sides of the post 13 and as stated these rollers are at the top of the support body, and the cables 20 are at the transverse centers.

The cables 20 pass over pulleys 21 mounted on the roof 11, and then are attached to counterweights 22 vertically slidably arranged on the rods 23 extending between the base 10 and the roof 11. Gate elements 24 project from the side ends of the support body 17. A vertical guide rod 25 with a serrated outer face 26 extends between the base and the roof. An arm 27 projects from the support body 17 and has an end roller 28 engaging against the serrated face 26 for vibrating or rocking the support body and attached gate elements sideways as they rise or descend for attracting attention. Base electromagnets 29 are mounted in the base 10 directly beneath the iron rollers 19.

As shown in Fig. 1, a gate device is placed on opposite sides of the tracks 30 and 31 at a road crossing 32. The tracks are divided by insulators 33 into gate operating sections 36 electrically connected with the electromagnets of the device as shown in Fig. 8, and ar-

ranged for completing an electrical circuit thru the magnets as a train passes thereover. A wire 34 connects one of the rails of each section to a battery 34' and one of the ends of the windings of the said electromagnets. A second wire 34^a connects the other rails of each section to a contact portion 34^b electrically engaged by a contact arm 17^a which is also engageable with contacts 14^a connected to the other ends of the windings of the said electromagnets.

A train passing over one of the gate operating sections 36 completes the electrical circuit across the rails thereof, and the arm 17^a normally connects with a contact 14^a connected with the electromagnets 14 in the uppermost position on the post 13 for energizing these particular magnets. The contact arm 17^a is carried on the support body 17. As the top electromagnets are energized the iron pulleys 19 are attracted and the support body 17 moves downwards. This downward motion breaks the connection between arm 17^a and the specified contact 14^a, but the momentum of the support body is sufficient to continue the downward motion until arm 17^a connects with a second contact 14^a connected with the magnets in the next to the uppermost position, which magnets then attract the pulleys 19 and the support body moves further downwards. The downward motion of the support body necessarily will be in steps and jerky for similarly affecting the gate elements for attracting attention.

Obviously as the top magnets are energized, the pulleys 19 are drawn downwards, and vibrate also as determined by the serrated face 26, then as the magnets next to the top position become energized the pulleys 19 and the gate, descend further, and so on until the gate is entirely closed as indicated by the dot dash lines 35 in Fig. 5. The electromagnets 29 are also connected with the track sections 36 and arranged for being energized for holding the gates closed until the train has passed the crossing. Then the counterweights return the gate elements to open position.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention what I claim as new and desire to secure by United States Letters Patent is:

1. A device of the class described, comprising a base, a roof spaced therefrom, a central post extending from the base to the roof, magnets mounted in vertical rows in the post, a support body slidably and vibratably mounted on the post, iron rollers on the support body for the magnet attraction, a means for normally urging the support body to top position, gate elements being mounted on the support body, a means for vibrating or rocking the gate elements and the support body during ascending and descending, and base magnets for holding the support body in lowest position.

2. A device of the class described, comprising a base, a roof spaced therefrom, a central post extending from the base to the roof, magnets mounted in vertical rows in the post, a support body slidably and vibratably mounted on the post, including top rollers bearing against the post and supporting cable attached on a center line for permitting the vibrating, iron rollers on the support body for the magnetic attraction, a means for normally urging the support body to top position, gate elements being mounted on the support body, a means for vibrating or rocking the gate elements and the support body during ascending and descending, and base magnets for holding the support body in lowest position.

3. A device of the class described, comprising a base, a roof spaced therefrom, a central post extending from the base to the roof, magnets mounted in vertical rows in the post, a support body slidably and vibratably mounted on the post, iron rollers on the support body for the magnet attraction, a means for normally urging the support body to top position, gate elements being mounted on the support body, a means for vibrating or rocking the gate elements and the support body during ascending and descending including an arm projecting from the support body and provided with a roller engaging a serrated face of a vertical mounted post, and base magnets for holding the support body in lowest position.

In testimony whereof I have affixed my signature.

ARMENAG TATIOSSIAN.
